UNITED STATES PATENT OFFICE.

JAMES C. SMITH, OF SAN FRANCISCO, CALIFORNIA.

ROTARY HOOK-SUPPORT FOR GARMENTS AND THE LIKE.

No. 812,691.

Specification of Letters Patent.

Patented Feb. 13, 1906.

Application filed May 10 1905. Serial No. 259,650.

To all whom it may concern:

Be it known that I, JAMES C. SMITH, a citizen of the United States, residing at San Francisco, in the county of San Francisco 5 and State of California, have invented certain new and useful Improvements in Rotary Hook-Supports for Garments and the Like, of which the following is a specification.

This invention relates to an improved rotary hook-support for hanging garments in wardrobes or closets or for supporting cups in china-closets or for similar purposes.

The object of the invention is to provide a device of this character which shall be convenient and durable in use, neat and attractive in appearance, and easily set up in position.

In the accompanying drawings, Figure 1 is a perspective view of the device. Fig. 2 is a 20 vertical section of the same.

Referring to the drawings, 1 represents a hollow metal body having a flange 2 adapted to rest against the under side of a shelf 3. At diametrically opposite points in said flange 25 are provided screw-holes 4 with countersunk heads, through which are passed screws 5, screwed obliquely into the shelf 3. This construction, with the oblique direction of the screws, is advantageous in two respects—first, it enables the screws to be screwed easily and conveniently into the under side of the shelf, and, secondly, the apparatus is very firmly secured by means of these oblique screws, since the pull upon the screws is not in the direction of the axis of the screw and is therefore 35 not resisted solely by the engagement of the thread of the screw of the wood of the shelf, but is at a considerable angle to said screws, and therefore tends to bind the screw in the wood. This is of especial importance on account of the fact that these shelves are generally made of cheap and soft wood, in which screws have a poor hold. Said body 1 has a 40 downwardly-extending crown-flange 6, and within said flange is received an upwardly-extending crown-flange 7 of a second hollow metal body 8, against the lower edge of which rests a cylindrical wooden block or support 9. Through the center of this block is passed a 45 vertical bolt 10, the head of which rests against the under side of the block 9, which

is recessed in the center, as shown. Upon the threaded portion of said bolt is first passed a nut 11, which is screwed down onto the top of the hollow body 8, firmly clamping 55 said casting and block together. The threaded end of the bolt is then passed through a boss 12 in the center of the upper body 1, being thus arranged centrally with reference to the flange 2, and upon the extreme end thereof are screwed a nut 13 and a lock-nut 14. Upon the periphery of the cylindrical block are secured by screws or in any other manner the hooks 15. The device is then ready to be secured to the under side of the shelf in the 60 manner already indicated.

The principal advantages of this construction are, in addition to the manner in which the body 1 is secured to the shelf, that the pivot about which the revoluble block 9, carrying the hooks, is rotated is entirely independent of the means for securing the whole device to the shelf. This renders it impossible for the apparatus to become loose from the shelf by the frequent rotation of the hook- 75 support about its axis. Furthermore, the hooks are detachable from the support, and any desired form of hooks can be attached to the apparatus or can be removed therefrom and replaced by others when desired. I also 80 regard as an important part of my invention the construction by which the bolt 10 serves, first, to secure together the two parts 8 and 9, and, secondly, to form an axis about which the block can revolve.

I claim—

1. A rotary hook-support comprising a body the upper edge of which is formed with upwardly and obliquely extending screw holes adapted to receive screws for securing 90 the same to the under side of a shelf or other support, a hook-carrier, a bolt passed through said hook-carrier axially thereof and also through said body centrally in respect to said flange, nuts on the end of said bolt, and 95 hooks secured to the periphery of said carrier, substantially as described.

2. A rotary hook-carrier comprising a hollow stationary member having a flange provided with means for securing the same to a 100 shelf or other support, a hollow revoluble member, a cylindrical hook-carrier, a bolt

passed centrally through said hook-carrier and revolute and stationary members, a nut firmly clamping the revolute member to the hook-carrier, a nut on the bolt attaching said 5 revolute member and hook-carrier to the stationary member, and hooks carried by said hook-carrier, substantially as described.

In witness whereof I have hereunto set my hand in the presence of two subscribing witnesses.

JAMES C. SMITH.
